UNITED STATES PATENT OFFICE

100,543

DESIGN FOR A PAPERWEIGHT OR LIKE ARTICLE

Daniel Leo Cullinan, Johnson City, Tenn.

Application April 3, 1936, Serial No. 61,927

Term of patent 7 years

To all whom it may concern:

Be it known that I, Daniel Leo Cullinan, a citizen of the United States, residing at 304 Peachtree Street, in the county of Washington and State of Tennessee, have invented a new, original, and ornamental Design for a Paperweight or like article, of which the following is a specification, reference being had to the accompanying drawing, forming part thereof.

Fig. 1 is a front elevational view of a paperweight showing my new design;

Fig. 2 is a top plan view thereof; and
Fig. 3 is a side elevational view.

I claim:

The ornamental design for a paperweight or like article as shown.

DANIEL LEO CULLINAN.
